UNITED STATES PATENT OFFICE.

JACOB HAISH, OF DE KALB, ILLINOIS.

SPARK-ARRESTER.

SPECIFICATION forming part of Letters Patent No. 378,092, dated February 21, 1888.

Application filed October 24, 1887. Serial No. 253,260. (No model.)

To all whom it may concern:

Be it known that I, JACOB HAISH, a citizen of the United States, residing at De Kalb, in the county of De Kalb and State of Illinois, have invented certain new and useful Improvements in Spark-Arresters for Locomotives; and I do hereby declare the following to be a full, clear, and exact description of the invention, such as will enable others skilled in the art to which it appertains to make and use the same, reference being had to the accompanying drawing, and to letters or figures of reference marked thereon, which form a part of this specification.

15 My invention has reference to certain improvements in locomotives, and has for its object the providing of certain apparatus and mechanism, by which the escape of sparks from the smoke-stack of such engine may be prevented.

20 In each section of the country railroads run through timber-land, in which in the fall of the year there is a large amount of dead leaves and other rubbish upon the ground, and in other cases there lie contiguous to the railroad-track fields of dry hay and grain-stubble, and almost invariably the right of way or sides of the track are covered more or less in the fall with dry weeds and grass. The 25 draft in its progression through the locomotive-flue is so great as to carry with the smoke sparks or small particles of fire, which very frequently ignite the dry rubbish along the track, and from these ignitions large and destructive fires are spread. It is obvious, also, that there is danger of such sparks setting fire to buildings located near the line of transit of the train. Various forms of spark-arresters have been devised and tried; but none of these 30 have thus far proved a perfect safeguard, as is evidenced by the constantly-recurring fires, caused as above described, sometimes continuing for days, and even weeks, in the timbered portions of the country. One mode has been

35 the seating transversely in the opening in the smoke-stack of one or more perforated horizontal partitions or sieves; but the interposition, in the path of the ascending smoke, of these horizontal sieves tends to impede the 40 necessary draft of the furnace, and therefore their use can be adopted to a very limited ex-

tent. This obstruction to the passage of the smoke has been sought to be obviated or neutralized by discharging the exhaust-steam into the accumulating smoke in the flue or smoke-stack, thereby forcibly ejecting the smoke; but this result has also the further effect of driving more or less of the sparks forcibly through the interstices in said sieve-like partitions, and thereby causes in some degree the very evil 50 which said sieves or partitions were designed to prevent.

45 In the drawing is shown a side elevation, somewhat in perspective, of a locomotive provided with my invention.

As the subject-matter of my invention is simply improvements upon or additions to any of the usual locomotives, I do not deem it necessary to show or describe the latter, further than will render intelligible a description of 70 the location, construction, and operation of my invention.

55 A is a locomotive provided with the usual horizontal boilers supported upon the driving-wheels B B and forward trucks C C.

60 D is the smoke-stack, consisting of the lower vertical portion, E, which has communication at its lower end with the forward end of the usual flues under and in the boilers, and has the central bend, F, toward the rear and the 80 upper vertical portion, G. Near the upper end of the vertical portion G is centrally located an annular horizontal plate, H, attached in any suitable way to the walls of the stack D, one mode being to connect the periphery 85 of the plate H to the walls of the flue D by radiating arms. The plate H is of necessity of less diameter than the vertical orifice in the stack D, within which it is suspended, an annular opening around the plate H being provided for the passage of the ascending smoke. Around the inner wall of the upper vertical portion, G, at about the plane of the bend F, 90 is seated downwardly and inwardly projecting annular flanges J.

95 The smoke in its ascension from the furnace is first made to deflect by the horizontal portion F' of the front wall of the stack D. A large proportion of the sparks which continue with the smoke upward within the annular flange J is by the latter arrested and thrown down upon the horizontal drawer K, leaving

the perforated top K' seated removably in the flue D directly below the plate H. Such of the sparks as pass through the flange J without contact with the latter are thrown against 5 the under surface of the annular plate H, and by the latter arrested and thrown downward upon and through the perforated top K' into the drawer K aforesaid.

L is a water-tube having communication at 10 its rear end in any suitable manner with the water in the usual water-tank carried in the tender, (not shown,) and projected in a substantially horizontal position along the side of the 15 locomotive A to a point on the side of the latter below and in the same vertical transverse plane with the plate H. From thence the tube L is turned upward and inserted within the smoke-stack D in such position that its upper end is directly under and but a short 20 distance from the plate H, and slightly higher than the highest water-mark in said tank. A small pump, M, is located at any suitable point in the tube L, and by means of steam carried thereto, in any of the usual modes, 25 from the steam-boiler, operates to draw the water from the water-tank and discharge the same vertically through the small opening in the upper end of the tube L against the lower surface of the plate H, from which the water 30 descends in a spray-like form down through the perforated top K' into the drawer K, and serves to extinguish the cinders which may fall therein. In the bottom of the drawer K there are also formed smaller perforations, K², which 35 permit the water to pass on downward into the filter N, seated beneath said drawer.

Unavoidably some of the smallest particles of cinders carried in solution in the water pass through the lower perforated plate, K², into 40 the filter N, and the function of the latter is to remove from the water these smaller particles. The bottom of the filter N has a funnel-like form, and at its lower projection communicates with the return water-tube O, which at its rear 45 end discharges the returning water into the water-tank.

The water aforesaid is utilized in a twofold manner: first, to extinguish the sparks, before described, in the drawer K, and, secondly, having been by its contact with the heated sparks warmed to a certain degree, it serves, when returned to the water-tank, to assist in raising the temperature of the water therein, preparatory to its use in the boiler or 55 steam-generator.

The drawer K, as before mentioned, is in-

serted removably in the rear wall of the stack D, and when filled with returning cinders can be readily removed, emptied, and replaced.

What I claim as my invention, and desire to 60 secure by Letters Patent of the United States, is—

1. In combination with the usual locomotive, a smoke-stack, D, having a deflected or angular interior and provided with the horizontal wall F, the annular flange J, and the suspended plate H, substantially as shown, and for the purpose described. 65

2. In combination with the usual locomotive, a smoke-stack, D, bent horizontally at or near its central portion, and provided with the annular flange J and suspended interior plate, H, and the inlet water-pipe M, adapted to discharge the water in small quantities against the under surface of the plate H, substantially 75 as shown, and for the purpose described.

3. In combination with the usual locomotive, a smoke-stack, D, provided with the suspended interior plate, H, and injecting water-pipe M, adapted to discharge a continuous 80 small stream of water against the lower surface of said plate, and the removable drawer K, having perforated upper and lower surfaces, K' and K², substantially as shown, and for the purpose described. 85

4. In combination with the usual locomotive, a smoke-stack, D, provided with the interiorly-suspended plate H, and induction-pipe M, provided with means for discharging a continuous small stream of water against the 90 under surface of said plate H, the drawer K, provided with the perforated top K' and perforated bottom K², the filter N, and return water-pipe O, substantially as shown, and for the purpose described. 95

5. In combination with the usual locomotive, a smoke-stack, D, provided with the horizontal wall F and interior annular flange, J, the interior plate, H, the discharge water-pipe M, adapted to deliver a continuous small stream 100 of water against the under surface of said plate H, the drawer K, provided with the perforated top K' and perforated bottom K², the filter N, and return water-pipe O, substantially as shown, and for the purpose described. 105

In testimony whereof I affix my signature in presence of two witnesses.

JACOB HAISH.
